UNITED STATES PATENT OFFICE.

EDWARD H. McCLOUD, OF COLUMBUS, OHIO, ASSIGNOR TO THE CENTRAL BRASS AND FIXTURE COMPANY, OF SPRINGFIELD, OHIO, A CORPORATION OF OHIO.

BUMPER.

Application filed September 27, 1928. Serial No. 308,718.

This invention relates to bumpers, and more particularly to bumpers composed of four separate pieces of material united in such a way as to be easily removed and replaced when broken.

It is an object of this invention to provide a bumper composed of two bumper bars and two back bars, with the back bars united at one end to the ends of the bumper bars and with their other ends united to the central part of the bumper bars in such a way as to have a sliding motion. These bars are held in relation to each other by bolts and nuts, together with suitable clamping members.

In the accompanying drawings there is shown a preferred embodiment of this invention, which is here used by way of illustration.

Figure 1 is a plan view of the bars assembled.

Figure 2 is a front view showing the bumper bars and the attaching plates.

Figure 3 is a plan view of one end of the bars.

Figure 4 is a front view of the parts shown in Figure 3.

Figure 5 is a section on the line 5—5 of Figure 4.

Figure 6 is an enlarged front view of the middle plate.

Figure 7 is a vertical section showing the means by which the inner ends of the back bars are attached to the front bars.

Figure 8 is a cross section through the middle plate showing the means by which the bars are connected at that point.

Figure 1 shows the parts of the bumper assembled in which the numeral 1 indicates the two front bumper bars proper. These bars are curved at each end, as indicated by the numeral 2, and have holes 3 therein for the reception of lugs or studs.

The back bar 4 is composed of two sections. The outer end of each section has a hole 5 therein for the reception of the bolt, by which it is attached to the outer ends of the front bars. Each of these back bar sections is provided, at its inner end, with a hole 6. The outer ends of these bars are attached to the front bars by means of a casing 7, which has a hole 8 therein. This hole is located in the central part of the casing, and on each end of the casing there is provided a stud member 9, which is adapted to enter the holes in the ends of the two front bars.

Each of the casings 7 is provided with side flanges 10, which overlap the side edges of the bars at the ends thereof. These casings also bend backwardly, as indicated by the numeral 11, at the end, so as to afford a glancing action when the ends of the bumper engage any object.

Each end casing is also provided with a projection 12 adapted to fit between the front bars and hold them in spaced relation while the ends of said bars are engaged by the casing and held by the studs 9 in the holes 3.

For the purpose of holding these parts in assembled relation there is a bolt 13, which passes through the casing 7 between the two front bars and through the hole 5. This bolt is held in assembled position by means of a nut 14, and for the purpose of preventing the nut becoming loose there is provided a lock-washer 15. The parts are united at the center of the front bars by means of a plate 16. This plate has projecting from the central part thereof a spacing stud 17 and has a bent part 18 at each end, which engages the outside edges of the front bars.

The plate 16 has a hole therethrough 19, adapted to receive a bolt 20. The bars are held in position by means of a clamping plate 21, which has a hole therein 22, adapted to receive the bolt 20. This clamping plate has the sides thereof bent down, as indicated by the numeral 23, to engage the outside parts of the inner ends of the back bar. When the bolt 20 is placed in position through the plate 16 and the clamping plate 21 there is engaging the end thereof a nut 24. This nut is held against turning on said bolt by means of a lockwasher 25.

When the parts are assembled, as shown in Figure 1, the outer ends of the bars are held in fixed relation to each other by means of the bolt, and the studs in the end casings. The inner ends of the back bars are held in sliding relation with the front bars. This is effected because the holes in the inner ends of the back bars are elongated and permit a longitudinal motion thereof on the stud 26 fitting in these holes.

It will also be observed that intermediate parts of the back bars, that is parts between the center and each end of the bumper, are spaced from the front bars. This affords a strengthening effect and affords means by which the bumper may be attached to the automobile.

I desire to comprehend within my invention such modifications as may be clearly embraced within my claims and the scope of my invention.

5 Having thus fully described my invention, what I claim as new and desire to secure by Letters Patent, is:

10 1. In a bumper, a front bar, a back bar composed of sections, one end of each section rigidly attached to one end of the front bar and the other end of each section slidably attached to the front bar for independent sliding motion.

15 2. In a bumper, a front bar, a back bar composed of sections, one end of each section rigidly attached to one end of the front bar and the other end of each section slidably attached to the middle of the front bar for independent sliding motion.

20 3. In a bumper, a pair of bumper bars, a back bar, means to engage all of said bars to hold said bumper bars in spaced relation to each other and the back bar in contact with the bumper bars so as to have only a longitudinal sliding motion on the bumper bars.

25 4. In a bumper, a pair of bumper bars, a back bar composed of sections, each section having a hole in one end thereof, and means to hold the bars in relation to each other, including means fitting in said holes to permit movement of each section in relation to the other and to said pair of bars.

30 5. In a bumper, a pair of bumper bars arranged in spaced relation to each other, a back bar composed of sections, each section having an elongated hole in the end thereof, a front plate engaging said pair of bumper bars and adapted to hold said bars in spaced relation to each other, a second plate having studs thereon adapted to engage the holes in said sections, and means engaging said plates to hold them in relation to said bars.

35 6. In a bumper, a pair of bumper bars held in spaced parallel relation to each other, a back bar composed of two sections, one end of each section being fastened to one end of said pair of bars, and the other end of each of said sections being fastened to the middle of said pair of bars so as to have movement to and from each other and longitudinal motion with relation to said pair of bars.

40 7. In a bumper, a pair of bumper bars, each bar having a hole in one end thereof, a

5 back bar having a hole in one end thereof, a casing having studs thereon fitting in the holes in said bumper bars and a central hole therein, and means passing through the hole in the casing and the hole in the back bar and adapted in cooperation with said casing to hold the bars in relation to each other.

60 8. In a bumper, a pair of bumper bars arranged in spaced parallel relation to each other, each bar having a hole in one end thereof, a back bar having a hole in one end thereof, said end in engagement with the hole end of said pair of bumper bars and across the space therebetween, a casing having studs thereon to engage the holes in said pair of bars and having a hole therein, and a bolt passing through the hole in the casing and the hole in the back bar to hold said bars in firm engagement with each other.

65 9. In a bumper, a bumper bar having a substantial bend at each end, a back bar composed of sections having an end of each section bent and in engagement with the bent parts of the bar, means substantially inclosing said ends of said bars and adapted to hold them in fixed relation to each other, and means to engage said bumper bar and the other end of each section to hold said ends in contact with said bar so that said ends may have longitudinal movement on said bumper bar.

70 10. In a bumper, a pair of bumper bars, each bar having a substantial bend at each end thereof, a back bar composed of sections each having one end thereof bent and in engagement with one bent end of each of the pair of bars, means substantially inclosing said ends and adapted to hold them in fixed relation to each other, and means engaging said bumper bars and the other ends of said sections to hold said ends in contact with the pair of bars so that said ends may have longitudinal movement on said bumper bars.

75 11. In combination in a bumper, spaced front bars, a pair of rear aligned bars located intermediate the horizontal planes of the front bars and in partial overlapping relationship, and a clamping member support extending between the front bars adapted to engage the front of the front bars and the rear of the inner ends of the rear bars slidably.

80 In testimony whereof, I affix my signature.

EDWARD H. McCLOUD.
